CLAIM

The ornamental design for a portable stand, as shown and described.

DESCRIPTION

FIG. 1 is a perspective view of a portable stand;

FIG. 2 is a front view;

FIG. 3 is a rear view;

FIG. 4 is a left side view;

FIG. 5 is a right side view;

FIG. 6 is a top view;

FIG. 7 is a bottom view; and,

FIG. 8 is an exploded view showing assembly of a top piece and a bottom piece of the portable stand.

Features shown in broken line in the various figures are for illustrating environmental structure and form no part of the claimed design.
